UNITED STATES PATENT OFFICE.

WILLIAM RIKER, OF PENN YAN, NEW YORK.

SAFETY-WINCH.

Specification of Letters Patent No. 19,263, dated February 2, 1858.

To all whom it may concern:

Be it known that I, WILLIAM RIKER, of Penn Yan, in the county of Yates and State of New York, have invented a new and useful Safety-Winch; and I do hereby declare that the following is a full, clear, and exact description of the same, reference being had to the annexed drawing, making a part of this specification, in which the figure is a 10 perspective view of the whole winch.

The part designated by letter A is the shaft to which the winch is applied, B the main arm or lever of the winch, C and C the ratchets placed on the shaft one on each 15 side of the lever with the face of one ratchet opposite to the other and fastened firm to the shaft or axle.

D and D are the pawls placed on the sides of the lever and are held to it by clasps and 20 may be fixed in grooves in the lever, they are also attached to the cross lever I, which holds them in position. The lever I, is fastened to the lever B, by a pin or bolt on which it turns freely.

25 E is a grooved pulley firmly attached to the handle G which is made to turn freely on a bolt that is firmly attached to the lever B at right angles with the same.

F is a small grooved pulley and is attached to the lever B by a pin or bolt on 30 which it turns freely.

H is a belt or band and is attached to one of the pawls D, between the handle G and pulley F, it is then passed around the pulley F then around the pulley E and attached 35 to the same pawl D with a spring if a non-elastic band is used or without a spring if there is sufficient elasticity in the band.

To use this winch the operator must take hold of the handle G, in the same manner 40 that he would an ordinary winch or crank and turn either direction and if he holds the handle with sufficient firmness he will cause one of the pawls to catch which will allow him to exert his force upon the shaft. 45 When the operator lets go the handle the pawl will leave the ratchet and the winch will hang down loose upon the shaft and there will be no danger from the winch if the shaft continues to revolve.

50 What I claim and desire to secure by Letters Patent is—

The means used to operate the pawls D and D substantially as above specified, also the ratchets C and C when used in combination with the devices above mentioned.

WILLIAM RIKER.
